COMBINATION ICE SCRAPER AND AUXILIARY SUN VISOR

Roger Fritz, Jackson, Minn., assignor of one-third to
Neil R. Tufvesson, Jackson, Minn., and one-third to
Silas H. Tufvesson, Jackson, Minn.

Filed Jan. 21, 1965, Ser. No. 83,505

Term of patent 3½ years

(Cl. D14—6)

FIG. 1

FIG. 2

FIG. 4

FIG. 3

FIG. 5

FIG. 6

FIG. 1 is a view in top plan of a combination ice scraper and auxiliary sun visor showing my new design;
FIG. 2 is an enlarged view in perspective of the top thereof;

FIG. 3 is a view in perspective of the bottom thereof;
FIG. 4 is a view in side elevation thereof, the side opposite that shown being a mirror image;

FIG. 5 is a view in rear elevation thereof, on a still further enlarged scale; and

FIG. 6 is a view in front elevation thereof.

The visor shown in broken lines in FIG. 1 is included for illustrative purposes only.

I claim:

The ornamental design for a combination ice scraper and auxiliary sun visor, as shown and described.
